DINNER PLATE

Edwin Denzl, Windischeschenbach, Upper Franconia,
Germany, assignor to Oscar Schaller & Co. Nachf.,
Bavaria, Germany, a firm of Germany

Filed Dec. 1, 1960, Ser. No. 63,058

Term of patent 7 years

(Cl. D44—15)

FIG. 1

FIG. 3

Fig. 1 is a top plan view of a dinner plate of conventional configuration, showing my new design, the motif of the rim continuing about the entire periphery thereof;

Fig. 2 is a sectional view on line 2—2 of Fig. 1; and

Fig. 3 is a sectional view on line 3—3 of Fig. 1.

I claim:

The ornamental design for a dinner plate, substantially as shown and described.
